DISTRIBUTOR CLUTCH FOR TYPOGRAPHICAL COMPOSING MACHINE

Paul Hilpman, Garden City, Leroy F. Albert, Brooklyn, and Harold Schad, Wantagh, N.Y., assignors to Mergenthaler Linotype Company, a corporation of New York

Filed July 29, 1958, Ser. No. 751,805

2 Claims. (Cl. 192—150)

This invention relates to typographical composing machines, such as Linotype machines of the general organization represented in U.S. Letters Patent to O. Mergenthaler, No. 436,532, wherein circulating matrices are released from a magazine in the order in which they are to appear in print and then assembled in line, the composed line transferred to the face of a mold, the mold filled with molten metal to form a type bar or slug, and the matrices thereafter returned through a distributing mechanism to the magazine from which they started.

In being distributed, the matrices are individually fed to a horizontal distributor bar, conveyed therealong by a set of rotating screws driven through a clutch arrangement from the intermediate drive shaft of the machine and, finally, released at different points along the bar for return to appropriate channels in the magazine. During the operation of the distributing mechanism, it sometimes happens that the rotation of the screws is abnormally resisted because of faulty distribution caused, for example, by a jammed matrix. In such cases, it is the function of the distributor clutch to break the driving connection between the intermediate shaft and the distributor screws in order to prevent damage to the parts.

While the distributor clutch arrangement employed in the past has proven satisfactory for many years, it has failed to meet the high standards of sensitivity required for modern high speed machines, such as those operated by automatic tape control units. Recent improvements in distributor clutches have therefore been directed toward increasing sensitivity in detection of abnormal resistance to screw rotation, and in reducing reaction time for stopping screw rotation once such resistance has been sensed.

The present invention provides an improved clutch device of greatly increased sensitivity and greatly reduced reaction time wherein positive locking of the driven clutch member against rotation is the primary reaction to screw rotation resistance, and disengagement of the clutch members is the subsequent reaction.

This and other improvements will be more fully pointed out in the detailed description which follows.

In the drawings:

Fig. 1 is a rear elevational view of the improved distributor clutch arrangement as applied to a Linotype machine;

Fig. 2 is a vertical cross-sectional view taken on line 2—2 of Fig. 1;

Fig. 3 is a vertical cross-sectional view taken on line 3—3 of Fig. 2;

Fig. 4 is a vertical cross-sectional view taken on line 4—4 of Fig. 1;

Fig. 5 is a horizontal cross-sectional view taken on line 5—5 of Fig. 1;

Fig. 6 is an oblique cross-sectional view taken on line 6—6 of Fig. 2; and

Fig. 7 is an oblique cross-sectional view taken on line 7—7 of Fig. 2.

During distribution, the matrices 10 are conveyed

2

along the distributor bar 11 by a pair of upper rotating screws 12 and a single lower rotating screw 13 until they arrive at their points of release and then permitted to fall by gravity through a short magazine entrance 14 into the appropriate channels of a matrix storage magazine (not shown).

The screws 12 and 13 are journally supported adjacent their ends in the horizontal cross piece of the distributor frame 15 of the machine. The upper screws 12 have little or no end play, but the lower screw 13, although normally banking against face 15a of the frame 15 (in Fig. 1) is permitted some slight axial movement in a leftward direction.

The distributor screws are constantly driven through a clutch from the intermediate drive shaft (not shown), which latter serves to drive a pulley 16 by means of a belt 19 (Figs. 1 and 3). The pulley 16 is rotatably mounted on a horizontal shaft 20 and is prevented from moving along the shaft by a collar 21 and a pin 22, diametrically disposed in shaft 20. The pin 22 also serves another function which will be described hereinafter. A driven disk 23, the facing 24 of which is adapted under normal circumstances to bear against the side of the drive pulley 16 to maintain frictional engagement therewith, is slidably disposed by means of a keyway on shaft 20. A serrated release plate 25 is rotatably mounted on shaft 20 adjacent the driven disk 23 and is resiliently coupled therewith. The driving connection to the upper screws 12 is completed through a gear 26 mounted on the shaft 20 and a gear arrangement denoted generally by the reference character 29, and in the case of the lower screw 13, through a gear 30 mounted at the left hand extremity of its supporting shaft (Fig. 1) which extends beyond the horizontal crosspiece of the distributor frame.

The horizontal shaft 20 is supported from a casting 31 of the distributor frame 15 and rotatably mounted in a bearing 32 thereof. As best shown in Fig. 3, the driven plate 23 has a hollow neck portion 23a which is provided with a key 33 arranged for longitudinal displacement in an elongated slot 34 formed in shaft 20 to permit the movement of the driven disk into and out of engagement with the drive pulley 16. A compression spring 35 surrounding the neck portion 23a is disposed between the bearing 32 and the driven disk 23, thereby normally serving to maintain the necessary frictional engagement between the disk and pulley. Referring to Figs. 2 and 7, the release plate 25 is coupled to the driven disk by two tension springs 39 extending between spring eyelets 40 on the plate and studs 41 on the disk. This type of connection is used to absorb a good portion of the shock which occurs when the locking mechanism, which will be described below, is thrown into operation. Two wedge-shaped release shoes 42 (Figs. 1, 2 and 3) are mounted on the release plate for cooperation with the pin 22, although normally the pin and shoes do not cooperate. An adjusting pin 38 (Figs. 2 and 6) is provided with an eccentric toe portion 38a to permit fine adjustment in positioning the shoes 42 with respect to the pin 22. The left end of the shaft 20 extends beyond the bearing 32 and has a knob 36 attached thereto (Fig. 1).

As explained above, to prevent damage to the matrices or to the machine parts when one or more matrices becomes lodged in the distributor screws, the lower screw 13 is permitted to float or yield axially in a rightward direction, in Figs. 1, 3 and 5, as a result of the camming action which will always occur between the rotating screw threads and the jammed matrix or matrices, and this axial movement of the lower screw 13 is utilized in the present invention to effect the disengagement of the clutch.

Toward this end, a U-shaped member 43 (Figs. 1, 4

3 and 5) sensitively serves to transmit the slightest rightward movement (in Figs. 1 and 5) of the lower screw 13 to the clutch locking mechanism. The member 43 is loosely mounted on a shaft 44 which is held fast adjacent its ends in the machine frame. A compression coil spring 45, which surrounds shaft 44, is disposed between one leg of member 43 and a collar 46, the latter being fixable on shaft 44, and serves to urge member 43 both to the left, along shaft 44, in Fig. 5, and in a clockwise direction in Fig. 4. The member 43 has three levers projecting therefrom. One lever 49, projecting vertically, carries a roller 50 which is biased against the right face of the gear 30 by spring 45, and thus serves to maintain the lower screw 13 in its normal leftward position. The same lever 49 also carries an adjustable finger 51 which is biased by the spring 45 into contact with a stud 52, adjustably mounted in the machine frame 57. It will be noticed that the finger 51 is so adjusted that it has contact with only a portion of the cross-sectional area of the stud 52. In this way, the slightest rightward movement of screw 13 will cause the finger 51 to be pushed off stud 52 thereby permitting spring 45 to pivot member 43 in a clockwise direction, in Fig. 4.

A second lever 53, projecting horizontally from member 43, has a finger grip 54 integral therewith, and carries a release plate stop or pawl 55 just out of the path of the release plate teeth (see Figs. 1 and 2). The spring 45 maintains the pawl 55 in constant readiness for engagement with the serrated release plate 25. This tendency is normally resisted by finger 51, until the finger is pushed off stud 52, at which time the stop 55 is permitted to engage one of the teeth of the rotating plate 25, thereby positively locking the plate against rotation. Immediately thereafter, pin 22, still rotating, engages the shoes 42, thereby camming plate 25 toward the left (Figs. 1 and 3) resulting in the movement of the driven disk 23 out of frictional engagement with the face of the drive pulley 16. It will be appreciated that in one motion the clutch has been locked out of operation and disengaged.

The third lever 56 projecting horizontally from member 43 normally holds a switch 59 (Fig. 4) in open position. Upon clockwise movement of member 43, lever 56 allows the switch 59 to close, thereby lighting a warning light.

Summarizing the operation of the improved clutch device, the driving mechanism for the distributor screws includes the driving pulley 16, the disk 23 frictionally driven by the pulley, the horizontal shaft 20 to which the driven disk 23 is keyed, and an arrangement of gears connecting the screws to the shaft. The frictional engagement between the driving and driven members is normally maintained by the compression spring 35. The lower screw 13, although normally positioned to the left by the action of the spring 45 and the roller 50, is capable of rightward axial displacement when one or more matrices become lodged in the distributor, and the slightest such displacement pushes the finger 51 off stud 52, permitting the release plate stop 55 to engage the release

plate and thereby lock the plate against further rotation resulting in the cooperation of pin 22 with the release shoes 42 to cam the driven disk 23 out of engagement with the driving member 16.

5 After having been disengaged, the clutch device can be quickly and conveniently reset in a single operation, once the troublesome condition has been eliminated. Toward this end, the operator need merely pull finger grip 54 downwardly, thereby rotating member 43 counterclockwise (in Fig. 4) to a position in which spring 45 can slide member 43 toward the left (Fig. 5) into normal position wherein finger 51 is once again disposed on stud 52.

10 The present invention has been shown and described in a single specific form and by way of example, but many variations and modifications may be made therein which will still be comprised within its spirit. It is to be understood, therefore, that the invention is not limited to any specific form or embodiment, except insofar as such limitations are specified in the appended claims.

What is claimed is:

15 1. Distributing mechanism for a typographical composing machine comprising rotatable screws for conveying matrices along a distributor bar, one of said screws being displaceable axially, a driven shaft for powering said screws, a driving member rotatably mounted on said shaft, a driven member keyed to said shaft and slidable thereon, a spring normally urging said driven member into engagement with said driving member in order to transmit power to said screws, a serrated release plate disposed adjacent said slidable member and resiliently coupled thereto, a pivotal member, a pawl integral with said pivotal member, said pivotal member being responsive to axial displacement of said distributor screw for permitting said pawl to engage said release plate thereby positively locking said plate against rotation, camming means mounted on said release plate, and a pin integral with said driven shaft positioned so as to engage said camming means upon the locking of said release plate,

20 30 35 40 whereby upon such engagement said driven member is separated from said driving member against the force of said spring.

45 2. Apparatus as described in claim 1 including means for adjustably positioning said release plate with respect to said driven member whereby the relative position of said camming means with respect to said pin may be adjusted.
